(57) **CLAIM**

The ornamental design for a television monitor, as shown and described.

DESCRIPTION

FIG. 1 is a perspective view of a television monitor showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a perspective view thereof showing the state in which the television monitor has been installed to a wall after the stand part has been detached;

FIG. 9 is a bottom view thereof with the base removed for ease of illustration; and,

FIG. 10 is an enlarged view of a part of the right part of the television monitor's main body.

The broken lines showing the wall in FIG. 8 are for illustrative purposes only, and form no part of the claimed design.
